UNITED STATES PATENT OFFICE.

JOHN HEARD, OF STRATHROY, CANADA.

BOTTLE-STOPPER.

SPECIFICATION forming part of Letters Patent No. 700,043, dated May 13, 1902.

Application filed August 6, 1901. Serial No. 71,076. (No model.)

To all whom it may concern:

Be it known that I, JOHN HEARD, a subject of the King of Great Britain, and a resident of Strathroy, in the Province of Ontario and Dominion of Canada, have invented a new and Improved Bottle-Stopper, of which the following is a full, clear, and exact description.

My invention is an improvement in that class of bottle-stoppers in which the body is recessed at its lower end and adapted to receive a conical plug which is drawn upward by means of some device or attachment, thereby expanding the lower end of the body, so that it will fit tightly in the bottle-neck.

15 The invention consists in the novel construction and combination of the several parts, as will be hereinafter fully set forth, and pointed out in the claims.

Reference is to be had to the accompanying drawings, forming a part of this specification, in which similar characters of reference indicate corresponding parts in all the figures.

Figure 1 is a vertical section through the neck of a bottle and a vertical section through the improved stopper. Fig. 2 is a vertical section through the body of the stopper, as shown in Fig. 1. Fig. 3 is a vertical section through a slightly-modified form of stopper. Fig. 4 is a vertical section through a stopper differing slightly in construction from the forms shown in the other views.

The neck A of the bottle to which the stopper is applied may be of any suitable or customary form. The stopper practically consists of four parts—namely, a body-section B, a plug or expanding section C, a cap-section D, and a locking-bar E, carried by the cap-section and having connection with the plug or expanding section. The parts may be 35 made of any suitable or approved material, and the exterior of the body-section, which section is adapted to enter the neck of a bottle, conforms exteriorly to the interior formation of the neck.

45 The body-section B is provided with a conical recess 11 in its bottom portion and with a bore 10, which extends from the recess 11 longitudinally through the body-section to the top thereof, as shown in Fig. 2. When 50 the stopper is constructed as illustrated in Figs. 1 and 2, the conical recess 11 in the bottom of the body-section is made of such width

at the bottom as to provide the body at its bottom portion with a feather-edge 12, which may be termed a "flange," and an elastic or yielding band 13, which may be attached to the feather-edge or flange, is passed around that section at its bottom portion in order that the said flange or feather-edge may adapt itself to any inequalities which may occur in 60 the inner face of the neck; but the band 13 is not absolutely necessary and may be dispensed with. The plug-section C is adapted to enter and slide in the conical recess 11 and conforms to said recess, said plug-section C 65 being of conical form, and this plug-section may or may not be provided with an exterior elastic band at its bottom portion in order that the plug-section may also by pressing against the inner surface of the flange or 70 feather-edge of the body expand the same, and thus accommodate it to any inequalities in the inner face of the neck of the bottle. This plug-section is usually provided at its upper central portion with a nut 14^a, adapted 75 to receive the threaded lower portion 15 of the locking-bar E, which locking-bar, under the construction shown in Fig. 1, is provided with a head 16, which is secured in the cap D in any suitable or approved manner. 80

In operation the plug C is loosely placed in position in the conical recess 11 of the body B. The locking-bar, attached to the cap D or otherwise, is passed down through the bore 10 in the body of the stopper until the threaded lower portion 15 of the locking-bar enters the nut 14^a in the plug C or a threaded aperture produced directly in the plug, or vice versa, when the locking-bar is carried by the plug-section C, (see Figs. 3 and 4,) which completes the assembling of the parts, and the stopper is ready to be inserted in the neck of the bottle, into which it is forced so far as desirable. Then by turning the cap D the locking-bar E is screwed into the plug C, drawing the said plug up into the recess 11 of the body B of the stopper, thereby expanding the feather-edge section 12 of the body of the stopper and causing the lower portion of the said body to be brought into firm and binding engagement with the neck, so that the stopper cannot be removed unless the plug C has been carried downward from the body. When the stopper is to be removed, the cap

D is turned in a reverse direction, partially unscrewing the locking-bar E from the expanding-plug C or cap D, and when the cap D is removed a certain distance from the top 5 of the body of the stopper the cap is given a quick sharp blow or firm pressure downward, which will dislodge the expanding-plug C and carry it from engagement with the bottom of the body of the stopper, enabling the 10 stopper, with all the parts, to be removed from the bottle.

It is obvious that a stopper of this description may be readily rendered aseptic and that the stopper may be repeatedly used until all 15 of its parts have become worn out.

The stopper described is capable of various modifications in its construction, and two additional forms of said stopper are shown in Figs. 3 and 4. Under the construction shown 20 in Fig. 3 the feather-edge is omitted from the bottom portion of the body B of the stopper, and the bottom edge surrounding the recess 11 is made straight, as shown at 17 in said Fig. 3. This straight or flat portion of the 25 bottom of the body engages with a round elastic ring or washer 19, fitted upon or above a shoulder 18 at the bottom of the plug, and the locking-bar E is provided with a bottom thread 15 and with an upper thread 20, or 30 otherwise, as shown in Fig. 1, the lower thread 15 entering directly into the expanding-plug C and may be attached to and carried by it, while the upper thread is made to enter a nut 20^a in the cap D or a threaded aperture 35 in the said cap, as may be desired. Under this form of stopper when it is placed in the neck of a bottle and the cap D is screwed down the plug C is drawn up in the recess 11 in the body of the stopper and the elastic or 40 yielding washer 19 is compressed and is forced against the inner face of the neck of the bottle, thus preventing the stopper from being withdrawn until tension on the washer 19 is removed.

45 In Fig. 4 I have illustrated a form of stopper which is particularly adapted for use in connection with large vessels, in which the body B is provided with a feather-edge 12 at its bottom and likewise has the bottom conical recess 11; but the expanding-plug C, which enters the recess 11, is provided with 50 an integral shank E', corresponding to the locking-bar E, (shown in the other views,) and a thread 21 is produced at the upper end 55 of the shank E', which thread enters a threaded aperture 22 in the cap D. Thus as the cap is turned down on the body of the stopper the expanding-plug is drawn upward in

the recess 11 in the body of the stopper, and the lower portion of the body is expanded or 60 forced outward to a locking engagement with the neck of the vessel in which the stopper may be placed. Elastic bands may be applied to this form of a stopper also. It will be understood that any other form of locking 65 device may be substituted for the bar E, capable of producing a like result.

It is apparent that the invention is applicable as a bung for casks of various kinds.

Having thus described my invention, I 70 claim as new and desire to secure by Letters Patent—

1. The improved bottle-stopper comprising a body having a conical recess in its lower portion, the walls of the latter being tapered 75 or beveled and the end of the same being flat as described, a conical plug conformed to and adapted to enter said recess and having an integral shaft provided with a cap for operating it, an expansible ring or washer interposed between the flat end of the walls of the body and a shoulder of the plug, whereby upon rotating the cap the plug is drawn into the said recess and the ring or washer expanded as described. 80 85

2. In bottle-stoppers, a body-section provided with a conical recess in its bottom portion, a conical plug adapted to enter the said recess, an elastic band located at the exterior of the parts of the body and compressed by 90 the action of the said plug when entering the recess in the body, a locking device connected with the plug, and a cap above the body of the stopper, likewise attached to the locking device, and through the medium of 95 which cap the locking-bar is manipulated, as described.

3. A bottle-stopper, consisting of a body provided with a recess in its bottom, an expansible ring at the lower portion of said body, an expanding-plug which enters the recess in the body, the entering portion of the plug being formed correspondingly to the inner contour of the said recess, a locking-bar connected with the plug, and a cap above 100 the body, connected with the locking-bar 105 and adapted in its operation to draw the plug upward in the said recess through the medium of the locking-bar, as set forth.

In testimony whereof I have signed my 110 name to this specification in the presence of two subscribing witnesses.

JOHN HIEARD.
